United States Patent Office.

C. W. HIGGINS, OF WAUKESHA, WISCONSIN.

Letters Patent No. 70,566, dated November 5, 1867.

IMPROVEMENT IN CHILDREN'S CARRIAGE AND CRADLE.

The Schedule referred to in these Letters Patent and making part of the same.

TO ALL WHOM IT MAY CONCERN:

Be it known that I, C. W. HIGGINS, of Waukesha, in the county of Waukesha, and State of Wisconsin, have invented a new and improved Combined Carriage and Cradle; and I do hereby declare that the following is a full, clear, and exact description thereof, which will enable those skilled in the art to make and use the same, reference being had to the accompanying drawings, forming part of this specification.

The present invention consists in so hanging or attaching the body of a children's carriage to the axles of the same that it can be readily attached and detached at pleasure, and in providing such body with rockers so that, when detached, it can be rocked upon the floor, whereby a combined carriage and cradle is produced. In the accompanying plate of drawings my improved combined carriage and cradle is illustrated—

Figure 1 being a view of the rear end of the same when together and in position for use as a carriage.

Figure 2, a central longitudinal vertical section, taken in the plane of the line x x , fig. 1, and

Figure 3 a transverse vertical section in the plane of the line y y , fig. 2.

Similar letters of reference indicate corresponding parts.

A, in the drawings, represents the body of the carriage, made of suitable form and shape, and at or near each end provided with a cross-piece, B, upon its under side, of a similar shape to the rockers of an ordinary cradle. C, stretcher-rods or bars extending from one rocker to the other one, by which rods C the body rests upon the rear or hind axle D, carrying a wheel, E, at each end, and are there fastened and held in place by bolt-pins a properly applied therefor and passed over them. F the reach-pole of the carriage. This pole passes through a loop, G, of the rocker to the front part of the body, and from thence through the rear axle D, wherein it is fastened by a bolt-pin, c , inserted therein. This reach-pole is extended so as to form a handle, H, for dragging the carriage by, and is also provided with a guide or front wheel, I, as in ordinary children's carriage.

From the above description of my improved combined carriage and cradle, it is plainly obvious that the results hereinbefore stated are secured, and that while it can be used as a carriage it is susceptible of being arranged as a cradle.

In lieu of fixing the rockers directly to the body, I have shown them as hung through cross-belts or straps L, thus making it freer and easier to the body when running as a carriage, or the body may be secured through springs for the same purpose.

I claim as new, and desire to secure by Letters Patent—

A children's carriage, when constructed substantially in the manner and for the purposes described.

C. W. HIGGINS.
